UNITED STATES PATENT OFFICE.

CHARLES S. BURTON, OF OAK PARK, ILLINOIS.

CONNECTOR FOR BED OR SEAT SPRING STRUCTURES.

1,347,989.

Specification of Letters Patent. Patented July 27, 1920.

Application filed November 3, 1919. Serial No. 335,541.

To all whom it may concern:

Be it known that I, CHARLES S. BURTON, a citizen of the United States, and a resident of the village of Oak Park, in the county of Cook and State of Illinois, have invented certain new and useful Improvements in Connectors for Bed or Seat Spring Structures, of which the following is a specification, reference being had to the accompanying drawings, forming a part thereof.

The purpose of this invention is to provide an improved connector for the parts of a spring bed or seat. It consists in the elements and features of construction shown and described, as indicated in the claims.

In the drawings:

Figure 1 is a plan view of a portion of a bed spring containing this invention.

Fig. 2 is an enlarged detail section at the line, 2—2, on Fig. 1, showing the connector in side elevation, one of the forms in which it may be embodied.

Fig. 3 is a section at the line, 3—3, on Fig. 2.

Figs. 4 and 5 are side elevations of the two parts of which the connector is comprised.

Fig. 6 is a plan view of a portion of a bed or seat spring having a connector of a modified form.

Fig. 7 is a section at the line, 7—7, on Fig. 6 on an enlarged scale.

Fig. 8 is a plan view of the load-supporting spring with which one end of the connector is engaged, and the two parts of the connector each shown in dotted line in the position relative to the spring for entering them upon the spring and in full line at the position fully engaged therewith and with each other.

Fig. 9 is detail section at the line, 9—9, on Fig. 7, view showing the two parts of the connectors fully engaged with each other and with the bed spring.

Figs. 10 and 11 are perspective views of the two parts of the connector.

Fig. 12 is a side elevation showing the manner of engaging the connector with the tie spring.

The drawings show a form of bed spring or seat spring which is familiar in its general character comprising vertically yielding main springs, 1, which it will be understood are helical coils, and a relatively small helical tie springs, 2, which are interlocked with each other by screwing one helix crosswise of the other, making a cross which has its

four ends positioned for being connected respectively with the four springs, 1, 1, 1, 1, which form a group around the cross. This invention relates to the form and construction of the connectors, A, by which the ends of the helical tie springs are connected with the respectively adjacent load-supporting springs, 1. These connectors are shown in two forms. In the form shown in Figs. 1 to 5 inclusive, each connector, comprises two parts, 3 and 4, each of which has at one end an open hook or eye for engaging the coil of the spring 1. These open hooks or eyes, 3^a and 4^a, have their openings in opposite directions so that they are adapted to be hooked onto the coil of the spring, 1, by hooking movement in opposite directions about that coil, so that when both are hookingly engaged with the coil, the opening of each eye or hook is lapped and closed by the other eye or hook, and by means of the two eyes or hooks, the engaged coil of the spring, 1, is completely encircled. At the opposite ends said parts, 3 and 4, have each a hook, 3^b and 4^b, for engaging the coil or coils of the tie spring, 2. These hooks, 3^b and 4^b, are both turned in the same direction, so that when the two connector members, 3 and 4, having their eyes, 3^a and 4^a, engaged with the coil of the spring, 1, are operated bodily as a unitary element, the same hooking movement—that is, a movement in the same direction—will engage both the hooks 3^b and 4^b, with the coil or coils of the tie springs. Intermediate their two hooked ends the two parts, 3 and 4, of the connector are interlocked with each other, as seen at 34, where the part, 3, whose eye, 3^a, opens downwardly for its engagement with the coil of the spring, 1, crosses under the part, 4, whose hook, 4^a, opens upwardly for its engagement with said coil of the spring, 1. Thus when the two hooks, 3^a and 4^a, are engaged by their opposite hooking movements with said coil of the spring, 1, and swung about said coil to each respectively close the opening of the other, they come into stopped engagement with each other at the crossing, 34; and by this means the two parts, 3 and 4, are adapted to be operated unitarily to swing the connector bodily about its pivotal engagement by means of the eyes, 3^a and 4^a, with the coil of the spring, 1, to engage the hooks, 3^b and 4^b, with the coils of the spring, 2.

In the form shown in Figs. 6 to 12 inclu-

sive, the eyes by which the two connector parts,—which in this form are designated 7 and 8, respectively,—are engaged with the coil of the spring, 1, are helical in form, 5 adapted to screw into each other, turning about the coil of the spring, 1, with which they are both engaged. This engagement by screwing together performs the same function for interlocking the two parts, 7 and 8, 10 which is performed in the previously described form by the parts crossing one above the other at 34. By this screwing engagement the opening of each eye is closed by the interlap of the other in the helix of the first, 15 and the disengagement of said two parts from the coil of the spring, 1, is rendered impossible except by the complete rotation of one or the other, or half rotation of both in opposite directions, such rotation being 20 rendered impossible by the engagement of the oppositely hooked ends, 7^a and 8^b, with the coils of the helical tie spring, 2, Fig. 8 shows in what manner the two parts, 7 and 8, are entered upon the coil of the spring, 1, 25 and positioned for being engaged with each other by screwing one into the other as described. For security of engagement of the connectors with the tie springs and protection against disengagement by accidental rotation of the tie springs which might unscrew them from the connectors, the end of the final coil of the tie spring is slightly bent out of its true helical or spiral position, as seen in Fig. 9, so as to contract the path be- 30 tween said end and the next coil or turn of

the spiral or helix to a distance less than the diameter of the wire forming the connector. This expedient is not claimed as a part of this invention, having been previously employed in other connectors. 40

I claim:—

1. In combination with two members of a spring structure to be connected, a connector comprising a two-part hook device, each part having at one end a hook for engaging 45 one of said members, and at the other end an eye for engaging the other member, said eyes being open for entering onto the member which they engage by hooking movement in opposite directions, said two parts 50 being adapted to interlock with each other in their said opposite hooking movement.

2. In the construction defined in claim 1 foregoing, the first mentioned hooks of said two parts being at the interlocked position 55 of the two parts, turned in the same direction for engagement of said first mentioned hooks of both of them with the first mentioned member by one and the same bodily hooking movement of said two-part device. 60

3. In the structure defined in claim 1, the oppositely open eyes of said two parts being helical and adapted to screw into each other, the interlocking of said parts being effected by so screwing said helixes together. 65

In testimony whereof I have hereunto set my hand at Chicago, Illinois, this 31st day of October, 1919.

CHARLES S. BURTON.
